C. A. ERICKSON

COMBINED HOLDER AND NOTCHER OR CUTTER FOR CASH TICKETS

Filed May 6, 1925

INVENTOR.

BY Charles A. Erickson.

Charles A. Erickson
ATTORNEY.

UNITED STATES PATENT OFFICE.

CHARLES A. ERICKSON, OF CHICAGO, ILLINOIS.

COMBINED HOLDER AND NOTCHER OR CUTTER FOR CASH TICKETS.

Application filed May 6, 1925. Serial No. 28,393.

To all whom it may concern:

Be it known that I, CHARLES A. ERICKSON, a citizen of the United States, residing at Chicago, in the county of Cook and State 5 of Illinois, have invented certain new and useful Improvements in a Combined Holder and Notcher or Cutter for Cash Tickets, set forth in the annexed specification.

This invention relates to improvements in 10 a device to be used in restaurants, drug stores, barber shops, and like places, by waiters, salesmen, or attendants to enable them to give to a customer a check, commonly called a cash ticket, properly marked 15 to indicate the amount of his bill or purchase to the cashier when presented to such persons for payment, and it consists in certain peculiarities of the construction, novel arrangements and operation of the various 20 parts thereof, as will be hereinafter more fully set forth and specifically claimed.

The tickets or checks for which the device is intended to be used for holding and notching, are furnished in the form of an 25 elongated rectangular tablet or pad of superposed tickets, each of said tickets usually being weakened in a transverse line near its top, by means of perforations, and each having on its front face near each of 30 its edges a column of numerals divided by short transverse lines, said numerals or numbers indicating cents and increasing from the numeral "5" in the ratio of five cents, up to any desired number or value.

The main object of the invention is, the provision of a device of the above mentioned 35 general character, which shall be of but few parts, simple and inexpensive in construction, strong, durable and efficient in its operation.

More specifically another object is the provision of a holder and notcher or cutter for checks or tickets, which can be, if desired, made of a single piece of material, 45 yet of such construction or form as to securely hold a tablet or package of superposed tickets in such a way that they may be easily separated and severed at a weakened point thereof, one at a time, and then cut or notched at a desired point in 50 one of its edges so as to remove one of the numbers representing the price of the cus-

tomer's purchase, as well as the amount to be paid to the cashier by the purchaser or customer.

Other objects and advantages of the invention will become obvious from the following description and explanation.

In the accompanying drawing which serves to illustrate embodiments of the invention—

Fig. 1 is a perspective view of one form of the device showing a pad of tickets held thereby.

Fig. 2, is a face view of the device with the tickets removed.

Fig. 3, is a side view, or edge view of the holder and notcher.

Fig. 4, is a rear face view of the upper portion of the holder.

Fig. 5, is a detached perspective view of a modified form of a member of the holder.

Fig. 6, is a view similar to Fig. 1, showing a modification in the holder and notcher.

Fig. 7, is a face view thereof, and Fig. 75 8, is an edge view of the same.

Like numerals of reference refer to corresponding parts throughout the different views of the drawing.

Referring now more particularly to Figs. 1 to 4 inclusive, the reference numeral 10 designates the body of the holder which consists of a rectangular plate having at one of its ends a transversely and forwardly disposed portion or top 11 of about the same width as that of the thickness of one of the pads of tickets. The front portion of the top 11, is bent or extended downwardly in parallelism with the body 10, for a short distance to form a portion 12, of the front part of the holder for the tickets, at their upper ends. The front holding part 12, is provided at its middle with a downwardly extended and outwardly curved tongue 13, which is by preference somewhat resilient and free to move.

As is clearly shown in Figs. 1 to 3, the lower portion of the part 12, is provided with a tubular bearing 14, having at its middle an upwardly extended angular cutting or notching member 15, which is disposed directly in front of the tongue 13, and co-operates therewith in cutting or notching the tickets. The upper portion of

the body 10, has punched therefrom midway between its edges an inwardly bowed clamping tongue or member 16, which rests against the rear upper portion of the pad 5 of tickets and assists in holding the same against the front holding part 12, of the holder.

The member 16, has a hook 17, at its lower edge for engagement with the rear portion 10 of a broken link 18, the spaced ends of which engage the bearing 14, at the lower front portion of the holding member 12, which portion of said members rest against the face of the pad slightly above the 15 weakened portions 19, of the tickets. Instead of employing a link 18 with its ends curved outwardly as shown in Figs. 2 and 4, a link 18^a, of rectangular shape as shown in Fig. 5, may be used for more securely 20 holding the pad or tablet of tickets in place, than if they were omitted.

The modification shown in Figs. 6 to 8, inclusive consists in omitting the member 16, from the upper portion of the body 10, 25 and in disposing the front holding portion 12^a, at an angle towards the body 10, instead of in parallelism therewith as in the other construction, also in providing said portion 12^a, with an angular notch 20, to co-operate 30 with a cutter 21, of similar shape and a size to enter the notch. The cutter 21, is fixedly mounted on the upper front transverse portion 22, of a substantially rectangular loop 23, which embraces the body 10, diagonally, 35 as shown. The transverse portion, or shaft 22 may be broken to allow its easy insertion into the tubular bearings 14 on the lower edge of the part 12^a, in which bearings said shaft is journaled for rotary movement.

40 It is obvious, that in the modified construction now under consideration, a pad of tickets can be readily inserted at its upper end into the space between the lower edge of the part 12^a, and the upper portion of the body 10, against the lower surface of the top 11, where it will be securely held in such a way that the weakened portions 19, of the tickets will lie approximately in line with the lower edge of the part 12^a, thus affording means as in the other construction for assistance in severing the tickets at their weakened portions, for it is manifest that by separating the front ticket at its lower portion from the tablet and properly manipulating it, the same can be easily torn from

the stub end of the tablet when either construction is used, after which, one of the side edges of the ticket can be placed between the cutter or notcher 15 and tongue 13, of the first described construction, with the numeral of the ticket indicating the purchase price, under the member 15, when it is apparent by pulling the ticket against the point of the said member, that portion of the ticket bearing the said price numeral will be removed, thus indicating when presented to the cashier the amount to be paid.

60 The same operation is carried out where the modified form shown in Figs. 6 to 8, inclusive is employed, except, that the ticket is 65 placed with its edge to be cut between the cutter 21, and front portion 12^a, when by pressing the lower portion of the member 23 towards the lower portion of the back of the body 10, it is obvious said cutter will co-operate with the notch 20, in the part 12^a to 70 clip out the price numeral of the ticket.

75 Having thus fully described the invention, what I claim as new and desire to secure by Letters Patent is—

80 1. In a device of the class described the combination with an elongated plate having at its upper end a forward disposed top portion provided at its front part with a downwardly extended front holding part for a package of tickets, said front holding part having at its lower edge a bearing, of a link embracing said plate and journaled in said bearing and a cutter extended upwardly 85 from said bearing and adapted to cooperate with said front holding part for forming a notch in a ticket.

90 2. In a device of the class described, the combination with an elongated plate having at its upper end a forwardly disposed top portion and below said portion a downwardly extended and inwardly positioned resilient tongue, said top portion provided at its front part with a downwardly extended holding portion for a package of tickets, said front holding portion having at its lower edge a bearing and about mid-way between its ends an upwardly extended cutting member, a cutter extended 95 upwardly from said bearing and adapted to co-operate with said front holding part for forming a notch in a ticket, and a link embracing said plate and journaled in said bearing.

100 CHARLES A. ERICKSON.
